UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

LEATHER-SKIVING MACHINE.

1,079,462.

Specification of Letters Patent.

Patented Nov. 25, 1913.

Application filed November 8, 1909. Serial No. 526,736.

To all whom it may concern:

Be it known that I, ALEXANDER M. ALEXANDER, a citizen of the United States, residing at Beverly, in the county of Essex and State of Massachusetts, have invented certain new and useful Improvements in Leather-Skiving Machines; and I do hereby declare the following to be a full, clear, and exact description of the invention, such as will enable others skilled in the art to which it appertains to make and use the same.

The invention relates to leather skiving machines, and more particularly to machines adapted to skive the edges of upper leather or leather of a similar character.

The invention is intended primarily as an improvement in the machine shown and described in the application of George E. Warren, Serial No. 481,117, filed March 3, 1909, although not confined in its application to such machine.

The object of the invention is to simplify and improve the construction and arrangement of various parts of a machine of this type whereby its operation is rendered more certain and reliable, and whereby the various adjustments requisite for enabling the machine to operate properly in doing various classes of work may be readily and conveniently effected.

To these ends the invention contemplates the provision in a machine provided with a cylindrical knife and a feed roll arranged within the knife to coöperate with a presser foot without the knife in presenting and feeding the material to the knife, of novel and improved means for varying the action of the knife upon the material in accordance with the character of the work being performed; the provision of novel and improved mechanism for so supporting the feed roll that it may automatically accommodate itself to variations in the position of the presser foot or variations in the thickness of the material being acted upon; the provision of novel and improved means for supporting and adjusting the grinder disk by which the cylindrical knife is sharpened; the provision of novel and improved means for adjusting the knife longitudinally to bring it into proper relation to the feed roll and presser foot and for firmly retaining the knife in adjusted position; and the

provision of novel and improved means for removing long strips of skiving from the interior of the skiving knife.

The invention also contemplates the provision of certain further features and combinations, the advantages of which will be obvious to those skilled in the art.

The various features of the invention will be understood from the accompanying drawings and the following detailed description of the machine shown therein.

In the drawings Figure 1 is a side elevation of a machine embodying the various features of the invention in their preferred forms; Fig. 2 is a plan view of the machine; Fig. 3 is a front end view with the front plate removed; Fig. 4 is a rear end view; Fig. 5 is a vertical longitudinal section through the axis of the cutter disk; Fig. 6 is a vertical transverse section on line 6—6; Fig. 2; Figs. 7 to 13 inclusive are detail views of the mechanism for supporting the feed roll; Fig. 14 is a plan view partly in section showing the means for driving the feed roll; Fig. 15 is a detail plan view of the devices for supporting and adjusting the grinder disk; Fig. 16 is an elevation of the devices shown in Fig. 15; Fig. 17 is a sectional view on line 17—17, Fig. 16; and Fig. 18 is a sectional view on line 18—18, Fig. 15.

In the machine shown in the drawings the various parts are supported upon a base which is in the form of a casing 1, the top plate of which forms a table for supporting the material to be acted upon. The machine is provided with a cylindrical knife 3 mounted within the casing 1 and projecting up through an opening in the table 2 into position to act upon the material. The material to be skived is presented and fed to the knife 3 by a feed roll 4 arranged within the knife and coöperating with a presser foot 5 arranged without the knife. The periphery of the feed roll is curved longitudinally to correspond to the curvature of the knife edge, and the engaging face of the presser foot 5 is concave, the curvature of its surface corresponding to the curvature of the knife edge. An adjustable side gage 6 is provided for guiding the edge of the material as it is fed to the knife.

The presser foot is carried by a block 7 mounted to slide vertically in guideways formed in the end of an overhanging arm 8. The block 7 is supported by a spring 9 which underlies the head of a stud 10 to the lower end of which the block is secured. The adjusting screw 11 engages the upper end of the stud 10, and by manipulating this screw the vertical position of the presser foot with relation to the knife may be readily and conveniently adjusted. In order that the angle of the bevel formed at the edge of the material by the skiving knife may be varied as desired, the presser foot is so mounted that it may be adjusted laterally as well as vertically. When the lateral adjustment of the presser foot is such that the concave surface of the foot is concentric with the knife, the knife will act along the line parallel to the surface of the presser foot, and when so adjusted the machine may be used for splitting strips of leather or reducing such strips to a uniform thickness. If it is desired to bevel the edge of the leather acted upon, then the presser foot is adjusted laterally toward the right in Fig. 3, and is adjusted vertically if necessary to bring the surface of the presser foot at the left side into a plane tangent to the cutting edge of the cutter. With the presser foot thus adjusted the knife will act to bevel the edge of the material fed between the feed roll and presser foot, and the angle of the bevel will depend upon the lateral adjustment of the presser foot. In order that a wide variation in the angle of the bevel cut by the knife may be secured, it is preferred to so mount the presser foot that its lateral adjustment is in a line inclined toward the knife in the direction of its travel. That is to say, the presser foot is so mounted that when it is adjusted toward the right or in a direction opposite to the travel of the knife it moves away from the knife, and when adjusted toward the left or in the direction of travel of the knife, it moves toward the knife. By thus mounting the presser foot to move laterally in an inclined line the distance between the surface of the presser foot and the knife at the right side of the presser foot rapidly increases as the presser foot is adjusted toward the right, while the relation between the surface of the presser foot and the knife at the left side of the presser foot remains substantially unchanged. The presser foot may therefore be readily adjusted to secure either a gradual or an abrupt bevel. Provision for conveniently securing this adjustment of the presser foot is made by mounting the presser foot in a laterally inclined guideway formed in the lower end of the block 7, and securing the presser foot in adjusted position by means of a spring

pressed locking pin 12, the inner end of which is arranged to engage any one of a series of notches 13 in the back of the presser foot.

The presser foot when adjusted is held in fixed position, and the material should be forced firmly and uniformly against the lower surface of the presser foot by the feed roll 4. In order that the feed roll may thus support the material, regardless of variations in the thickness of the material being operated upon, and of variations in the adjustment of the presser foot, mechanism is provided for so supporting the feed roll that it may tip to change its angle with relation to the presser foot and skiving knife, and may move bodily toward and from the presser foot. As shown, the feed roll is mounted upon a stud 14 projecting from a block 15 which is pivotally mounted upon the end of a supporting lever 16. The pivot pin 17 upon which the block 15 is mounted is so arranged that its axis is in a plane at right angles to the axis of the feed roll. Movement of the block 15 about the pivot pin 17 therefore causes a tipping of the roll 7 to vary its angle with relation to the presser foot in accordance with the variations in the thickness of material, or to change its angle with relation to the skiving knife in accordance with the adjustment of the presser foot. The normal position of the feed roll is determined by two co-operating stops on the block 15 and lever 16 respectively, which are held in engagement by a torsional spring 18 which surrounds the pivot pin 17 and connects the block and lever. As shown, the co-operating stops consist of a plate 19 secured to the block 15 and projecting into position to engage the side 20 of the lever 16 (Figs. 7 and 8).

The lever 16 is pivotally mounted upon a supporting rod 21, the axis of which is substantially parallel to the axis of the feed roll and in a plane at right angles to the axis of the knife. Movement of the lever about the rod 21 therefore moves the feed roll bodily toward or away from the knife and presser foot. The normal position of the lever is determined by a lug 22 projecting laterally from the lever and arranged to engage the end 23 of a slot 24 which is formed in a collar 25 secured to the shaft 21. The end 23 of the slot and the lug 22 thus form a fixed abutment and stop for determining the normal position of the roll supporting lever. The lever is supported in normal position by a torsional spring 26 which surrounds the hub 25' of the collar 25 and is connected with the lever and collar. In order that the force with which the feed roll is pressed against the material may be readily varied in accordance with the character of the material being operated

upon, means is provided for varying the tension on the torsional spring 26. In the construction shown this means comprises a sleeve 27 to which the end of the spring 26 is secured. This sleeve is mounted upon the hub 25 and is provided with a spring pressed pawl 28 arranged to engage a series of ratchet teeth 29 formed on the hub. The sleeve 27 is also provided with a handle 30 through which it may be readily manipulated. When it is desired to increase the tension on the spring 26, the sleeve 27 is moved in the direction of the arrows, Figs. 11 and 12, the ratchet 27 riding over the teeth 29 and retaining the collar in its adjusted position. When it is desired to decrease the tension on the spring, the pawl 28 may be readily disengaged from the ratchet 29 and turned in the opposite direction, the pawl being reengaged with the ratchet when the proper adjustment is secured. A second spring 31 may be interposed between the lug 22 and the end of the slot 24 to assist in supporting the feed roll and holding it yieldingly in normal position. In case it is desired to move the feed roll bodily away from the presser foot or knife, this may be readily done by means of a handle 32 projecting from the lever 16.

In order that the knife 3 may be readily sharpened as occasion may require, the machine is provided with a grinding disk 33. This disk is carried by a slide 34 which is secured upon an arm or lever 35. The slide 35 is guided upon the arm 35 by a lug 36 which projects through a slot 37 formed in the slide, and the slide is held upon the arm by means of screws 38 passing through slots 39 in the slide. An adjusting screw 40 is provided for readily and conveniently adjusting the slide upon the arm 35 to vary the position of the grinding wheel longitudinally of the knife in accordance with the bevel which it is desired to give the knife edge. The arm 35 is mounted upon centers 41 so that the end carrying the grinding wheel may be moved toward and from the knife 3. In order that the arm 35 may be readily manipulated to bring the grinding disk into and out of engagement with the knife, a link 42 is connected with the front end of the arm 35 and is extended through an opening in the side of the casing 1. A spring 43 is interposed between a shoulder on the link and the inner side of the casing, and tends to force the arm 35 toward the cutter. The outer end of the link 43 is screw-threaded and is engaged by a nut 44 provided with a knurled head 45. The nut is held in position by a plate 46, the upper end of which is bifurcated and engages an annular groove 47 in the nut.

The cylindrical knife 3 is secured upon the end of a shaft 48 which is mounted in 65 a bearing sleeve 49. In order that the knife may be readily adjusted longitudinally to bring it into proper relation to the feed roll and presser foot as it is ground away, the bearing sleeve 49 is mounted so that it may 70 be moved longitudinally, and the rear end of the shaft 48 is connected by a telescoping coupling 50 with a driving shaft 51. In the construction shown the sleeve 49 is mounted to move longitudinally in a split 75 bearing 52 formed in a frame 53 which is supported within the casing 1, and is also provided with bearings for the shaft 51. In order that the sleeve may be conveniently adjusted longitudinally it is provided with 80 a rack 54 arranged to be engaged by a pinion 55 formed on a transverse rod or shaft 56. The shaft 56 is extended out through the side of the casing and is provided at its outer end with a knurled head 57 by 85 which it may be readily rotated in effecting the longitudinal adjustment of the knife shaft 48. For the sake of simplicity the rod or shaft 56 is also utilized as the means for operating the split bearing 52 to clamp 90 and release the bearing sleeve 49. As shown the inner end of the shaft 56 is provided with a nut and washer 58 arranged to engage the inner side of the bearing 52, and the shaft is also provided with a screw- 95 threaded portion 59 at the point where it projects beyond the casing 1. A nut 60 engages the screw-threaded portion 59 and is arranged to bear against a face 61 on the side of the casing. By screwing up the 100 nut 60, the rod 56 may be operated to contract the split bearing 52 and thus clamp the bearing sleeve 49 firmly in adjusted position. The tightening of the screw 60 also serves to lock the shaft 56 against rotation so that manipulation of the knurled head 57 is prevented. When the nut 60 is screwed away from the face 61 the split bearing 52 is released so that the sleeve 49 may be adjusted longitudinally, and the 110 shaft 56 is also unclamped so that it may be turned to adjust the sleeve longitudinally.

In operating upon some classes of work the skiving knife removes a long continuous skiving or strip from the material, and in such case this strip is liable to be engaged by the edge of the knife and to be carried up and wound around the feed roll or otherwise interfere with the proper operation of the machine. In order to avoid this the machine is provided with a deflector plate 62 arranged in front of and projecting into the knife into close proximity to its inner surface beyond the cutting point. The plate is dished or curved so that the skiving re- 120 moved by the cutter is engaged by the plate and directed out away from its edge. The deflector plate is preferably secured to a

bracket 63 extending forward from the front end of the frame 53 so that it may be readily removed in case the machine is to be used upon a class of work which results in the removal of short skivings or chips.

10. The feed roll 4 is driven through a shaft 64, the inner end of which is connected through a universal joint with one end of a shaft 65, and the other end of which is connected through a universal joint to the roll. The shaft 64 is provided with a worm wheel 66 which is engaged by a worm 67 (Fig. 15) secured to one end of a shaft 68, the other end of which carries a pulley 69. 15. The shaft 68 is driven from the driving shaft 51 through a belt 70 which passes over the pulley 69 and over a pulley 71 secured to the driving shaft. The grinding wheel is driven from the driving shaft 51 20. through a belt 72 which passes over a pulley 73 secured to the driving shaft, over idler pulleys 74, and about a pulley 75 secured to the grinding disk shaft. The idler pulleys 74 are mounted upon a swinging 25. arm 76 which may be adjusted through a lever 77, to keep the belt tight under the various adjustments of the grinding disk.

While it is preferred to employ the specific construction and arrangement of parts 30 shown and described, it will be understood that this construction and arrangement is not essential except so far as specified in the claims, and may be varied and modified without departing from the invention.

35. Having explained the nature and object of the invention, and specifically described one form of machine in which it may be embodied, what I claim is:

1. A leather skiving machine, having, in 40 combination, a cylindrical knife, a feed roll within the knife, and a concave fixed presser foot without the knife the position of which determines the bevel cut having provision for lateral adjustment to vary the bevel cut 45 by the knife, substantially as described.

2. A leather skiving machine, having, in 50 combination, a cylindrical knife, a feed roll within the knife having its periphery curved longitudinally to correspond to the curvature of the knife, and a fixed presser foot the position of which determines the bevel cut having an engaging face curved to correspond to the curvature of the knife and having provision for lateral adjustment to 55 vary the bevel cut by the knife, substantially as described.

3. A leather skiving machine, having, in 60 combination, a cylindrical knife, a feed roll within the knife, and a concave presser foot having provision for adjustment laterally in a line inclined toward the knife in the direction of its travel, substantially as described.

4. A leather skiving machine, having, in

combination, a cylindrical knife, a fixed 65 presser foot having a concave engaging surface and having provision for lateral adjustment to vary the bevel cut by the knife, and a feed roll within the knife having its periphery curved longitudinally to correspond to the curvature of the presser foot, 70 and mounted to yield angularly and bodily toward and away from the presser foot, substantially as described.

5. A leather skiving machine, having, in 75 combination, a knife, a presser foot, a co-operating feed roll, a block on which the roll is mounted, a spring supported lever on which the block is pivoted to tip to vary the angle of the roll with relation to the presser 80 foot and knife, cooperating stops on the lever and block, and a spring for holding the stops in engagement, substantially as described.

6. A leather skiving machine, having, in 85 combination, a knife, a presser foot, a co-operating feed roll, a block on which the roll is mounted pivotally supported to tip about an axis located in a plane at right angles to the axis of the roll, a lever on 90 which the block is pivoted supported to turn about an axis located in a plane at right angles to the axis of the knife, a spring between the lever and block for yieldingly supporting the roll, and a spring supporting 95 the lever, substantially as described.

7. A leather skiving machine, having, in combination, a knife, a presser foot, a co-operating feed roll, a block on which the roll is mounted, a lever mounted to turn 100 about an axis parallel to the axis of the roll, a pivotal connection between the block and lever the axis of which is located in a plane at right angles to the axis of the roll, a torsional spring connecting the lever and 105 block, and cooperating stops on the block and lever held in engagement by said spring, substantially as described.

8. A leather skiving machine, having, in 110 combination, a knife, a presser foot, a co-operating feed roll, a lever on which the roll is yieldingly mounted to tip to change its angle with relation to the presser foot and knife, a torsional spring acting on the lever to support the roll, and means for 115 varying the tension of the spring, substantially as described.

9. A leather skiving machine, having, in 120 combination, a knife, a presser foot, a co-operating feed roll, a lever on which the roll is yieldingly mounted to tip to change its angle with relation to the presser foot and knife, a torsional spring for supporting the lever having one end connected to the lever, a sleeve connected to the other end 125 of the spring, and means for adjusting the sleeve to vary the tension on the spring, substantially as described.

10. A leather skiving machine, having, in combination, a knife, a presser foot, a co-operating feed roll, a lever on which the roll is mounted, a torsional spring having 5 one end connected to the feed roll lever, a sleeve connected to the other end of the spring, a pawl carried by the sleeve, and a ratchet engaged by the pawl to hold the sleeve in adjusted position, substantially as 10 described.
11. A leather skiving machine, having, in combination, a presser foot, a feed roll, a longitudinally movable sleeve provided with a rack, a shaft journaled in the sleeve, a 15 knife mounted on the shaft, a split bearing for the sleeve, a clamping rod for operating the bearing to clamp and release the sleeve provided with a pinion for engaging the rack on the sleeve, substantially as 20 described.
12. A leather skiving machine, having, in combination, a presser foot, a feed roll, a longitudinally movable sleeve, a shaft journaled in the sleeve, a knife mounted on the 25 shaft, a bearing for the sleeve, and means for adjusting the sleeve longitudinally and for clamping the sleeve in the bearing, substantially as described..
13. A leather skiving machine, having, in combination, a presser foot, a feed roll, a longitudinally movable sleeve, a shaft journaled in the sleeve, a knife mounted on the shaft, a split bearing for the sleeve, and a device for adjusting the sleeve and contracting and releasing the bearing, substantially as described.
14. A leather skiving machine, having, in combination, a presser foot, a feed roll, a longitudinally movable sleeve provided with a rack, a shaft journaled in the sleeve, a 40 knife mounted on the shaft, a split bearing for the sleeve, a clamping rod for contracting and releasing the bearing, and a pinion on the rod engaging the rack on the sleeve, substantially as described.
15. A leather skiving machine, having, in combination, a cylindrical knife, an arm movable toward and away from the periphery of the knife, a slide mounted on the arm for movement longitudinally of the 45 knife, an adjusting screw for moving the slide, and a grinding disk mounted on the slide, substantially as described.

ALEXANDER M. ALEXANDER.
